INVENTOR,
Joseph E. Renne
BY
John Edward.
ATTORNEY

UNITED STATES PATENT OFFICE.

JOSEPH E. RENNE, OF PATERSON, NEW JERSEY.

YIELDING PITMAN FOR LOOMS.

Application filed August 18, 1923. Serial No. 658,014.

To all whom it may concern:

Be it known that I, JOSEPH E. RENNE, a citizen of the United States, residing at Paterson, in the county of Passaic and State of New Jersey, have invented certain new and useful Improvements in Yielding Pitmen for Looms, of which the following is a specification.

This invention relates to looms and in particular to the means for connecting the batten with the crank-shaft of a loom whereby to impart movement from the latter to the former. The object of the invention is to provide an improvement in that class of such connections in which provision is made for permitting a cushioning of the beating-up stroke imparted by the crank-shaft to the batten and thereby reducing the harshness of the beating-up impact of the reed against the fell of the fabric and also saving the breaking of parts of the loom frequently caused by shock incident to such beating-up stroke, especially when the protecting mechanism of the loom acts to check the batten suddenly during such stroke. The improvements are directed to certain structural features of such a connection designed to make it simple and inexpensive to manufacture and easily applied to a loom, while preserving it fully efficient in action.

In the accompanying drawing,

Fig. 1 is a side elevation of the improved connection, or pitman, the crank-shaft and batten bearing member also appearing (in section);

Fig. 2 is a plan of what appears in Fig. 1;

Fig. 3 shows two parts *g* and *l* in longitudinal section; and

Fig. 4 is a section on line 4—4, Fig. 1.

The crank-shaft of a loom is shown at *a* and the bearing member by which the batten (not shown) is connected therewith through the improved pitman is shown at *c*.

The body structure of the pitman includes a metal strap *d* having its end portions rebent to form opposite and reversed loops *d'* and *d''*; its extremities are here shown bent outwardly in the same direction and penetrated and connected by a bolt *e* having a nut *f* and a lock-nut *f'*; by forming the strap in the way shown and described the cost of manufacture thereof will be reduced and the assembly therewith of the other parts will be simplified. The two loops receive the crank of the crank shaft

and the journal *c'* of the member *c* and afford bearings therefor, as will appear.

In the loop (*d'*) which receives said journal *c'* is fitted a bearing member in the form of a block *g* which has tapped into it a longitudinal hole *g'* into which is screwed the threaded reduced end of a stem *h* extending toward the other loop and held from turning by a lock-nut *i* thereon screwed up against the block. The block and the loop are penetrated by a bolt *j* having a nut *j'* and thus serving to clamp the block rigidly in place; thus the block and stem become parts of the body structure, rigid with respect to the strap *d*. On the threaded portion of the stem *h* is a nut *k* affording an abutment; it is kept from turning by a lock-nut *k'*.

In the other loop (*d''*) is arranged another bearing member in the form of a block *l* having a longitudinal hole *l'* receiving with a sliding fit the smooth free end of stem *h*. This block is guided for rectilineal movement, only, in the strap *d* in part by stem *h* and in part by opposite lugs *m* which play in slots *n* formed in the strap.

Both blocks are outwardly recessed to afford bearings which are complementary to the bearings afforded at the bends of the loops in strap *d* and the several bearings may be lined with Babbitt or other half-bushings *o* to fit the crank of the crank-shaft, and the journal *c'*; when the parts *o* are employed they may be riveted in place as indicated at *p*.

Between the block *l* and the abutment *k* and penetrated by stem *h* is a helical spring *r*; the tension of the spring may be varied as conditions require by adjusting the nut *k* on the stem.

When the device is in use and the crank-shaft imparts the beating-up stroke to member *c* and hence the batten carrying the latter the shock will obviously be absorbed by the spring, thereby greatly reducing the harshness of the impact of the reed against the cloth and saving breakage and general wear and tear of the loom parts, in the latter case especially when the batten is suddenly stopped by the going into action of the protecting mechanism of the loom.

It is not new to provide a connection between the crank-shaft and batten of a loom affording an elastic cushion and being thus adapted to absorb the shock incident to the beating-up stroke of the crank-shaft; but

so far as I am aware those combinations of parts which are set forth in the appended claim, involving a strong, durable, inexpensive and easily assembled yet efficient pitman of the yielding class, are new.

Having thus fully described my invention, what I claim and desire to secure by Letters Patent is:

A yielding pitman including a strap having its end portions rebent to form opposite and reversed loops, removable means

to connect the extremities of the strap, a bearing in one of the loops, a bearing member arranged in the other loop and slidable toward and from the end of the pitman corresponding to said loop, and means, including a spring, normally opposing movement of said member toward the other end of the pitman.

In testimony whereof I affix my signature.

JOSEPH E. RENNE.
